CLAIM

The ornamental design for a marine windlass, as shown and described.

DESCRIPTION

FIG. 1 is a top plan view of a marine windlass showing our new design;

FIG. 2 is a bottom plan view thereof;

FIG. 3 is a side elevational view thereof, the opposite side elevational view being a mirror image of that shown; and

FIG. 4 is a top perspective view thereof.

FIG. 1

FIG. 2

FIG. 3

FIG. 4
